UNITED STATES PATENT OFFICE.

FRANK W. OFELDT, OF JERSEY CITY, NEW JERSEY, ASSIGNOR TO THE MARINE VAPOR ENGINE COMPANY, OF SAME PLACE.

VAPOR-ENGINE.

SPECIFICATION forming part of Letters Patent No. 540,757, dated June 11, 1895.

Application filed January 18, 1893. Serial No. 458,821. (No model.)

To all whom it may concern:

Be it known that I, FRANK W. OFELDT, of Jersey City, in the county of Hudson and State of New Jersey, have invented certain new and useful Improvements in Vapor-Engines; and I do hereby declare the following to be a full, clear, and exact description of the invention, such as will enable others skilled in the art to which it appertains to make and use the same.

My invention relates to an improvement in engines, and more particularly to such as employ vapor as the motive power,—the object of the invention being to produce a simple and efficient engine adapted to be operated by means of vapor and to produce effectual apparatus for supplying the engine with such motive power.

A further object is to provide simple and efficient reversing mechanism for the engine.

A further object is to produce a vapor engine which shall be of compact construction and effectual in the performance of its functions.

With these objects in view the invention consists in certain novel features of construction and combinations and arrangements of parts, as hereinafter set forth, and pointed out in the claims.

In the accompanying drawings, Figure 1 is a sectional view of the engine. Fig. 2 is a side elevation of the engine, partly in section. Fig. 3 is a view illustrating the retort-chamber and pump for supplying fuel to the retort-chamber. Fig. 4 is a plan of the retort-chamber and retorts. Figs. 5 and 6 are views illustrating the pump for supplying the retorts with the liquid to be vaporized. Figs. 7, 8, and 9 are detail views.

A represents the casing of a triple cylinder single acting engine, having cylinders B, B, B,—each of which communicates with a central chamber C.

The casing A is made with an annular chamber or passage C' adapted to communicate with the valve chests or chambers D of the various cylinders.

The main shaft E of the engine, is provided, at a point centrally located within the chamber C, with a crank arm E', to which the piston rods E² of the various pistons E³ are con-

nected, said piston rods being provided in proximity to the point of connection with the crank arm with flat faces a, whereby the movement of said piston rods relatively to the 55 other will be properly limited.

Mounted within the casing A in alignment with the main shaft E is a sleeve F, from which an arm F' projects, said arm being provided with a perforation for the reception of 60 the free end of the crank pin E', whereby the motion of the crank arm will be imparted thereto to cause the rotation of the sleeve F. Located within the sleeve F and adapted to rotate with it is another sleeve G having a 65 spirally formed opening for the reception of a spiral groove b in a shaft G'. A sleeve H is loosely mounted on the shaft G' and is made with a groove c, in which a spline or feather c' projecting from the shaft G' projects, so 70 that the rotation of said shaft G' will be imparted to the sleeve H.

Secured to the sleeve H is an eccentric H', with which a pitman H², is connected by means of an integral strap H³, the other end 75 of said pitman (or more properly speaking, valve rod) being connected with a valve I, which reciprocates between the wall of the annular chamber C' within the valve chamber and a plate I', said plate being adjustably supported by means of a screw d passing through the casing of the engine.

The valve I is made with an opening e adapted to connect the port 1 from the annular chamber C', with the port 2, which communicates with the end of the cylinder. Each of the several cylinders are, of course, provided with these ports, valve chambers and valves. One only of the valves I is provided with the pitman H² having the integral strap 85 H³. The other two valves have links H⁵ connected with them at one end, and at their other ends are pivotally connected with ears c² projecting from said strap or eccentric.

When the parts are in the positions shown 95 in Fig. 1, the valve I is in position to supply vapor to the cylinder shown in section, but when said valve and piston move upwardly, the vapor under the piston will exhaust through the port 2 into the valve chamber, 100 under the valve, from which it will pass through an opening e' in a plate J, into the

central chamber C, from which it passes through an outlet port 3 to a pipe, by means of which it is conveyed to a condenser of any suitable construction.

5 A stirrup f is swiveled to the outer end of the shaft G', and to this stirrup a lever K is pivoted at a point between its ends. The free end of the lever K is pivotally connected to a link f', and the latter is pivotally connected to an ear or lug f² projecting from the casing of the engine. By operating this lever, a longitudinal movement can be imparted to the shaft G', whereby to cause the sleeve G on said shaft to make a partial revolution and thus reverse the engine.

A retort chamber L is mounted on the engine casing, and is provided with a perforated boss g, as shown in Fig. 5, for the passage of a pipe g', said pipe communicating at its lower end with the inlet port g², shown in Figs. 1 and 2. The main body of the retort chamber L is preferably composed of asbestos g³ secured to and supported by thin metallic cylinders g⁴, and the base L' of said retort chamber or cylinder is made dish-shaped as shown in Fig. 3. A coil or retort L² is located in the bottom of the retort chamber and communicates with a pipe L³. A series of coils or retorts M communicate at one end with the pipe or retort L², and at their other ends with a stand-pipe or chamber, preferably at the upper end of the latter. The stand pipe M' communicates with the pipe g' and rests upon a stand M² located in the bottom of the retort chamber, said stand being provided with openings h for the passage of heat from a burner below it, to the retorts in the retort chamber, as will be hereinafter more particularly explained.

In order to maintain the retorts supplied 40 with the liquid to be vaporized (preferably alcohol), the devices now to be described will be employed.

The pipe L³ communicates with a pump N located on the engine casing, and said pump 45 also communicates with a condenser or tank (not shown), from which the supply of alcohol or other suitable liquid is forced by said pump into and through the retorts, said pump being provided with the usual inlet and outlet valves i, i'. The plunger N' of the pump N has a pitman N² connected with it, said pitman terminating in a band or strap N³, which encircles and receives a reciprocating motion from an eccentric N⁴ carried by the 50 main shaft E, whereby said pump will be kept continuously in operation while the engine is running.

In order to heat the retorts in the retort chamber and thus vaporize the alcohol or 60 other volatile fluid injected into said retorts, the devices now to be described will be employed.

The bottom of the retort chamber L is made with openings j for the admission of air to 65 support combustion of oil within the chamber. A pipe O passes through one of these openings and after being coiled about the

pipe g', extends downwardly and inwardly and terminates over a cup O' located in the bottom of the retort chamber,—said pipe being provided at or near its end, on the top, with a jet or perforation j'. The pipe O is connected with a valve O², said valve also having a pipe O³ connected with it, the other end of which latter pipe communicates with a 70 pump P. The pump P also communicates, by means of a suitable pipe, with an oil supply tank, not shown. A link k is connected at one end with the plunger p' of the pump P and at the other end is connected with a 80 lever Q at a point between the ends of the latter. The lever Q is provided at its free end with a plate l which rests on an eccentric R carried by the engine shaft E. A spring S is attached at one end to the lever Q at a point 85 between its fulcrum and the point of attachment thereto of the link k, and at the other end said spring is attached to a projection from the pipe O³.

From this construction and arrangement 90 of parts it will be seen that the lever Q and consequently the plunger P' of the pump P, will be moved in one direction by the eccentric R and in the reverse or return direction by the spring S. It will also be seen that as 95 the engine operates the pump P will be kept in operation to force oil through the pipes O³ and O. When the apparatus is started a small quantity of oil will flow through these 100 pipes into the cup O', the oil being made to thus flow through these pipes (when or before the engine begins to run) by operating the pump P manually by operating a handle S' projecting from the fulcrumed end of the lever Q. When sufficient oil shall have entered the cup O' it will be lighted, thus to 105 heat the pipes directly above it. When the pipe O shall have become sufficiently heated the oil therein will become vaporized and burn at the jet j' the flame shooting upwardly 110 and the heat passing upwardly through the openings h in the stand M² and heating the 115 retorts to vaporize the alcohol or other liquid in said retorts, and also retain the coil of the pipe O sufficiently heated. The vapor created 120 in the retorts will flow into the stand pipe M' and from thence through the pipe g' into the annular chamber of the engine from whence it passes through the valve chambers into the cylinders, to operate the engine as above explained. From the engine, after performing its work, the vapor is exhausted as above 125 explained and passes to a condenser (not shown)—from which it is again pumped to the retorts by means of the pump N.

In order to lubricate the engine, lubricating oil can be introduced with the motive power, and said motive power (vapor) will cause the lubricant to thoroughly and effectually lubricate the working parts of the engine.

A guard T is employed within the bottom of the retort chamber, which extends downwardly and terminates over the upper edge of the cup O'.

Having fully described my invention, what I claim as new, and desire to secure by Letters Patent, is—

1. The combination of a vapor engine of three cylinders arranged at an angle to each other, pistons moving therein, a crank shaft common to all of the pistons, valve devices for admitting vapor to the cylinders successively, two eccentrics moved by the crank shaft, and two independent pumps operated by said eccentrics, whereby definite relative quantities of liquids are moved commensurate with each revolution of the engine.

2. The combination in a vapor engine of three cylinders arranged at an angle to each other, pistons moving therein, a crank shaft common to all of the pistons, valve devices for admitting vapor to the cylinders successively, an inclosing case inclosing the working parts of the engine, an eccentric secured to the crank shaft and inclosed within said casing, and a pump operated by said eccentric and supported by said casing whereby the pump structure is protected.

3. The combination in a vapor engine of three cylinders arranged at an angle to each other, pistons moving therein, a crank shaft common to all of the pistons, valve devices for admitting vapor to the cylinders successively, an inclosing case inclosing the working parts of the engine, an eccentric secured to the crank shaft and inclosed within said casing, a pump operated by said eccentric and supported by said casing whereby the working parts of the pump are protected, an eccentric or cam device also operated by the crank shaft and arranged exterior to the engine casing, and a second pump operated thereby.

4. The combination with two or more cylinders, and pistons operating therein, of a shaft having a crank thereon, piston rods extending from one end of this crank to the pistons, a revolvably supported sleeve extending

over or overlapping the crank having an arm projecting therefrom, and a pin from the 45 crank connected with valves for the cylinders connections between the valves and sleeve, and adapted to revolve the sleeve, substantially as set forth.

5. The combination with two or more cylinders, pistons therein, a shaft having a crank thereon, and piston rods extending from one end of the crank to the pistons, of a revolvably supported sleeve extending over or overlapping the crank having an arm projecting 55 therefrom and connected with and adapted to turn the sleeve with the crank, slide valves, an eccentric for operating the valves, and means projecting inwardly through the sleeve and overlapping the crank for reversing the 60 valves, substantially as set forth.

6. The combination of two or more cylinders, pistons therein, a crank shaft, bent piston rods extending from the pistons to one end of the crank, a sleeve structure revolvably 65 supported in the wall of the engine overlapping the crank and provided with an arm connected with the crank and an internal spiral groove or grooves, a slide shaft having a spiral guide thereon which operates in connection with a corresponding spiral groove or 70 grooves formed in the sleeve structure and overlapping the crank, a second sleeve arranged concentric with said slide shaft and having a sliding connection therewith but rotatable with it, an eccentric secured to this second sleeve, valves for the cylinders, and 75 strap heads connecting the valves to the eccentric.

In testimony whereof I have signed this 80 specification in the presence of two subscribing witnesses.

FRANK W. OFELDT.
